HOLDER DEVICE FOR END-CAPPED ELECTRICAL DISCHARGE TUBES PROVIDED WITH STARTER SWITCHES

Erik Gunnar Holm, Hagalund, Sweden, assignor to Lumalampen Aktiebolag, Stockholm, Sweden, a corporation of Sweden

Application February 2, 1948, Serial No. 5,804
In Sweden August 24, 1946

Section 1, Public Law 690, August 8, 1946
Patent expires August 24, 1966

3 Claims. (Cl. 173—328)

1

This invention relates to fittings or holders for fluorescent tubes and starter switches and more particularly to such a fitting comprising a plurality of separable parts which may be selectively and variably assembled in accordance with the requirements of several types of such electrical fixtures.

In one form of electrical fixture of the character with which we are here concerned, the fluorescent tube sockets and ballast impedance for the tube are generally placed beneath a reflector designed to conceal the ballast and electrical wiring. In such fixtures the starter switch is usually located behind the reflector, in a laterally disposed projection or portion of one of the tube holders. Generally the starter switch is positioned perpendicularly to the longitudinal axis of the fluorescent tube and projects through an appropriate aperture in the reflector, thus facilitating replacement when necessary.

In another form of such electrical fixture, fluorescent tube sockets, ballast impedance and starter switch are mounted upon or in front of the reflector which comprises a mounting plate or base and one of the tube sockets is provided with a holder for the starter switch. In such circumstances the starter switch is usually positioned in parallelism with respect to the longitudinal axis of the fluorescent tube, thereby obviating the manufacturing expense incident to the laterally projecting starter switch holder of the aforementioned type of device.

In a still further type of fixture, the fluorescent tube sockets are manufactured without any holder for a starter switch, the switch being located independently of the tube holders, or other starting means being provided. It will thus be obvious that heretofore it has been necessary to provide a variety of types of fluorescent tube holders to accommodate different mounting requirements. In addition, the varying forms of tube holders resulted in structural differences in the associated parts of the electrical device.

Accordingly, it is a major object of the present invention to provide a novel holder of standardized form for fluorescent tubes and starter switches so that each of the several types of electrical fixtures discussed hereabove may be conveniently accommodated.

Briefly stated, the invention comprises a socket for a fluorescent tube, an adapter for mounting said socket in the electrical fixture or device, and a holder for a starter switch, the adapter and starter switch holder being manufactured with substantially identical exterior conforma-

2

tion or dimensions. Thus, if it is desired to assemble a fixture with the starter switch mounted perpendicularly with respect to the longitudinal axis of the fluorescent tube, the tube holder is mounted upon an adapter, the upper surface of the adapter and the lower surface of the base of the tube socket being of complementary conformation, and the starter switch holder is mounted upon a side wall of the adapter. In contradiction, if the starter switch is to be disposed in parallelism with respect to the axis of the fluorescent tube, the adapter may be omitted and the starter switch holder is placed upon its side and fastened directly to the bottom wall of the tube holder, the side of the starter switch holder and the bottom wall of the tube holder being of complementary conformation. In both instances the other fluorescent tube socket, it being obvious that two sockets are required, is mounted upon an adapter. In addition, the invention contemplates providing the adapters and starter switch holder with apertures so located as to register with apertures in the base of the tube socket, thus, when either an adapter or a starter switch holder is employed to mount the tube holder, the same fastening elements may be employed to complete the assembly.

The accompanying drawing illustrates one practical embodiment of the invention which will be described in detail to enable others to understand and use the same, but the invention is not considered restricted to the specific construction shown in the drawing and reference is therefore had to the claims for summaries of the essentials of the invention and of the novel features of construction and of the novel combinations of parts for all of which protection is desired.

As shown in the drawing:

Fig. 1 is a side elevational view, partly in section, illustrating one assembled form of the invention with the fluorescent tube sockets mounted upon adapters and with the starter switch holder mounted upon a side wall of one of the adapters, the starter switch being disposed perpendicularly with respect to the longitudinal axis of the tube.

Fig. 2 is a side elevational view, partly in section and somewhat similar to Fig. 1, illustrating one of the fluorescent tube sockets mounted upon a starter switch holder, the adapter being omitted and the starter switch being disposed in parallelism with respect to the longitudinal axis of the tube.

Fig. 3 is a top plan view, on a slightly enlarged scale, of the starter switch holder.

Fig. 4 is a top plan view, also on a slightly enlarged scale, of one of the adapters.

As shown in the drawing, particular reference being had to Fig. 1 thereof, a fluorescent tube 1 is mounted or supported between a pair of tube sockets 3 in the usual manner and as is well known in this art, the end closures or caps 2 of the tube being provided with the usual contact members (not shown). Each tube holder is provided with an enlarged foot portion or base 5 and is mounted upon an adapter 6, the upper surface of the adapter and the lower surface of the base being of substantially identical dimensions and peripheral conformation. Suitable fastening elements 22 such as screws, bolts, or the like, extend through aligned apertures in the base 5 and adapter 6 for securing the tube sockets to the mounting plate or base 9 of the electrical fixture. As shown more particularly in Fig. 4 of the drawing, the adapter is provided with apertures 21 for this purpose.

The starter switch holder 10, which has substantially identical exterior dimensions as the adapter 6, is secured to a side wall of the adapter by screws, or the like, extending through suitable apertures 18 provided in the starter switch holder. In the form of assembly illustrated in Fig. 1, the starter switch holder is so positioned that the recess 11, intended for the reception of the starter switch 12, faces upwardly; thus, the starter switch is disposed perpendicularly with respect to the longitudinal axis of the fluorescent tube 1.

In the type of electrical fixture thus described, the tube sockets 3 and adapters 6, one of which carries the starter switch holder 10 and starter switch, are mounted upon or secured to the base plate 9 beneath the reflector 14, the latter being provided with opposed apertures 4 through which the fluorescent tube holders 3 project. Thus, the lowermost portions of the tube sockets, the adapters, starter switch holder, electrical wiring and ballast or choke coil 15, which is mounted upon the base plate 9 as indicated in dotted lines, are concealed from view. The reflector if further provided with an additional aperture 13 through which the starter switch 12 projects. Removal of the starter switch or the replacement thereof, when necessary, is a particularly simple task since the switch is thus conveniently accessible.

In the form of electrical fixture illustrated in Fig. 2 of the drawing, the mounting plate or base 9 comprises the reflector and the several parts are mounted directly thereupon. As shown, the starter switch 12 is disposed in parallelism with respect to the longitudinal axis of the fluorescent tube, the starter switch holder 10 being substituted for the adapter 6 employed when the starter switch is vertically disposed. The assembly of this form of the invention is particularly simple. The starter switch holder 10 is positioned on a side thereof beneath the base 5 of the tube socket, with the starter switch recess 11 facing toward the opposed tube socket which is mounted in the usual manner upon an adapter 6. The exterior conformation of the side of the starter switch holder upon which the tube socket is mounted is substantially identical to that of the base 5 of the tube socket and the apertures 18 are in vertical alignment with the apertures in said base, the identical fastening elements 22 previously described passing through said aligned apertures and securing tube socket and starter switch holder to the mounting plate or base of the fixture. Thus the

method of attaching the tube socket to the mounting plate is identical whether the socket be supported upon an adapter or a starter switch holder, these elements being selectively interchangeable in accordance with the type of mounting desired.

The starter switch 12 is mounted in its recess 11 in the following manner, as is customary in this art. The starter switch is provided on its lower surface with a pair of pins, contact members 8 being secured to the lower extremities of these pins. The bottom wall of the recess 11 in the starter switch is provided with opposed apertures 16 communicating with reduced arcuate slots 17 providing the usual bayonet type of locking connection. The contacts 8 are receivable within the apertures 16 and partial rotation of the starter switch positions the disc pins within the slots 17 to lock the starter switch in position with the disc 8 in engagement with suitable spring contact members (not shown). Preferably the sides of the starter switch holder are provided with recesses 19 and 20 and the adapter 6 is provided with a vertically disposed cavity or bore 7 for the reception of suitable electrical wiring.

The novel electrical fitting described herein comprises a fluorescent tube socket, an adapter, and a starter switch holder which may be selectively and variably assembled with the starter switch disposed either vertically or horizontally, as may be desired, and without requiring any alteration in either the associated parts or the fastening means whereby the separable parts or elements are attached to the mounting base. In addition, if desired, the tube sockets may be secured directly to the mounting base with the adapters omitted and other starting means may be employed or a starter switch holder may be secured to the opposed side or surface of the mounting base, directly beneath and in alignment with one of the tube sockets.

It will be obvious to those skilled in this art that various changes may be made in the invention without departing from the spirit and scope thereof and therefore the invention is not considered limited by that which is illustrated in the drawing and described in the specification but only as indicated in the appended claims.

50. What I claim is:

1. A combined fluorescent tube socket and starter switch holder comprising separable members including a fluorescent tube socket, an adapter for supporting said socket, said adapter being provided with a bore for the reception of electrical connections, securing means for attaching said socket to said adapter, the socket and adapter being provided with aligned apertures for the reception of said securing means, and a starter switch holder, said starter switch holder being provided with spaced apertures for the reception of fastening means whereby said starter switch holder may be secured to one face of said adapter, the starter switch holder and adapter being of substantially identical exterior conformation whereby the starter switch holder may be supported in a plurality of positions by selectively employing the adapter to mount the fluorescent tube socket or substituting the starter switch holder for the adapter, the spaced apertures in the starter switch holder aligning with the apertures in the tube socket whereby the socket may be attached to the starter switch holder using said securing means.

78. 2. A combined fluorescent tube socket and

starter switch holder comprising separable members including a fluorescent tube socket, an adapter for mounting said socket, one face of said adapter being complementary to the lower face of the base of said socket, said adapter being provided with a bore for the reception of electrical connections, securing means for attaching said socket to said adapter with said complementary faces in superposed relationship, the socket and adapter being provided with aligned apertures for the reception of said securing means, and a starter switch holder, said starter switch holder being provided with spaced apertures for the reception of fastening means whereby said starter switch holder may be secured to a face of said adapter, the starter switch holder and the adapter being of substantially identical exterior conformation whereby the starter switch holder may be supported in a plurality of positions by selectively employing the adapter to mount the fluorescent tube socket or substituting the starter switch holder for the adapter, the spaced apertures in said starter switch holder aligning with the apertures in the tube socket whereby the socket may be attached to the starter switch holder using said securing means.

3. A combined fluorescent tube socket and starter switch holder comprising separable members including a fluorescent tube socket provided with a rectangular base, a substantially rectangular adapter for mounting said fluorescent tube socket, one face of said adapter being complementary to the lower face of said rectangular base, said adapter being provided with a bore for the reception of electrical connections, securing

means for attaching said socket to said adapter with said complementary faces in superposed relationship, the socket and adapter being provided with aligned apertures for the reception of said securing means, and a substantially rectangular starter switch holder, said starter switch holder being provided with spaced apertures for the reception of fastening means whereby the starter switch holder may be secured to a face of said adapter, the starter switch holder and the adapter being of substantially identical exterior conformation whereby the starter switch holder may be supported in a plurality of positions by selectively employing the adapter to mount the fluorescent tube socket or substituting the starter switch holder for the adapter, the spaced apertures in the starter switch holder aligning with the apertures in the tube socket whereby the socket may be attached to the starter switch holder using said securing means.
